UNITED STATES PATENT OFFICE.

KARL EGGART, OF ARBON, SWITZERLAND, ASSIGNOR TO THE FIRM OF ADOLPH SAURER, OF ARBON, SWITZERLAND.

EMBROIDERING-MACHINE.

1,123,504.

Specification of Letters Patent.

Patented Jan. 5, 1915.

Application filed February 3, 1914. Serial No. 816,145.

To all whom it may concern:

Be it known that I, KARL EGGART, a citizen of the Republic of Switzerland, residing in Arbon, Switzerland, have invented 5 certain new and useful Improvements in Embroidering-Machines, of which the following is a specification, reference being had to the accompanying drawings, which form a part hereof.

10 This invention relates to the suspension and counter-balancing of the work frames of embroidering machines and especially of automatic or jacquard embroidering machines. In such machines the work frames 15 are sometimes counter-balanced by weights and sometimes by springs.

The present invention is concerned particularly with the counter-balancing of the work frame by a spring and it has for its 20 object to provide simple and effective means for equalizing the counter-balancing force exerted by the spring throughout the range of movement of the work frame, regardless of the variation in the tension of the spring. 25 The counter-balancing spring is necessarily very stiff and as the range of movement of the work frame is considerable, the tension of the spring, whether of one form or another, varies considerably at the extremes 30 of movement. It may happen, therefore, that if the frame is properly counter-balanced at one extreme of its movement it may be either over-balanced or under-balanced, as the case may be, at the other extreme 35 position. The result is an impairment of the quality of the embroidery produced.

In accordance with this invention the difficulty is overcome and uniform counter- 40 balancing of the frame in all positions is secured by varying the effective length of the lever arm through which the spring acts upon the suspension system, or, in other words, in varying the leverage through 45 which the spring so acts, with the tension of the spring. That is, when the work frame is at one extreme position and the tension of the spring is at its minimum the leverage upon the suspension system 50 through which the spring acts is minimum and its applied force is greater, and when the frame is at the opposite extreme and

the tension of the spring is at its maximum the leverage through which the spring acts is at its maximum and its applied force is 55 less. Thereby the counter-balancing force delivered to the suspension system from the spring is substantially equalized and uniform throughout the range of movement of the frame. 60

The invention will be more fully explained hereinafter with reference to the accompanying drawings in which it is illustrated and in which—

Figure 1 is a view in front elevation of 65 the frame of an embroidering machine with its work frame, suspension levers and connections to the counter-balancing spring and to the jacquard or automat. Fig. 2 is a view of the same in end elevation as seen 70 from the right hand in Fig. 1 but on a larger scale. Fig. 3 is a view in front elevation of the parts shown in Fig. 2 and on the same scale as Fig. 2.

The present improvements, so far as they 75 relate to the counter-balancing of the work frame, may be employed with various systems of frame suspension, but for purposes of illustration of the invention they are shown in the accompanying drawings and 80 will be described herein as employed in connection with a system of frame suspension such as that which is made the subject of another application for Letters Patent of the United States filed concurrently herewith Serial No. 816,146. This system of suspension will be described as far as may be necessary to enable the application of the present improvements to be understood 85 clearly. 90

In the drawings the jacquard or automat, indicated generally at 1, is shown as having a shaft 2 provided with a beveled gear 3 which meshes with a beveled pinion 5 on a vertical screw shaft 4 supported at its 95 upper end by a bracket 9. On the screw shaft is a traveling sleeve or nut 6 which engages a rod 7 pivotally connected at its upper end to the suspension lever 10 which is pivotally mounted at 11 on the machine 100 frame 8 and to the horizontal arm of a three-armed lever 12 which is pivotally mounted at 13 on the machine frame 8. The upper arm of the three-armed lever 12

is connected by a tension member 14 with the bell crank suspension levers 15 (one or more) suitably distributed and supported upon the machine frame. The lower arm 5 of the three-armed lever 12 is connected by a tension member 16 with a substantially vertical arm 17 which is secured to a shaft 21 mounted in brackets 25 26 secured to the machine frame 8. The shaft 21 also has 10 secured thereto an arm 22 which is connected by a tension member 23 with the suspension system, as through one of the suspension levers 15. The arms 17 and 22 with the shaft 21 constitute a lever through 15 which not only is the suspension system connected, for movement in one direction, to the jacquard or automat, through the medium of the three-armed lever 12, but through which the counter-balancing force 20 of the compensating spring hereinafter referred to is also applied to the suspension system and therefore to the work frame 36. The tension members 14 and 16 are shown as supported at intermediate points, as at 25 18, 19 and 20, to prevent sagging. Also mounted in the brackets 25 26 is a shaft 27 which may have secured thereto a worm gear 28 for engagement by a worm 29 suitably supported by the bracket 25 and provided with a squared shaft for convenient 30 engagement by a key or wrench for the purpose of adjusting the tension of the counter-balancing spring 31, which has one end secured to the gear 28, as at 32, and the other 35 end secured, as at 33, to a tension arm 34 through which the counter-balancing force of the spring is communicated to the lever arm 17. The shafts 21 and 27 are relatively displaced or eccentrically mounted, 40 with the shaft 21 on that side of the shaft 27 toward which the tension arm 34 moves with increasing tension of the spring 31. Provision is made for operative connection between the tension arm 34 and the lever arm 17, such that when the tension arm 34 moves in a direction to increase the tension of the spring 31 the leverage through which the spring acts upon the suspension system is decreased, and vice versa. This result is 45 conveniently accomplished by mounting the tension arm 34 and the lever arm 17 as described and providing the tension arm 34 with a bearing surface 35 for engagement by a roller 24 carried by the lever arm 17, so that the tension arm and the lever arm have a movable or shifting point of engagement and that the effective length of the tension arm varies with the position of the tension arm and therefore with the tension 50 of the spring 31. The bearing surface is preferably straight and nearly radial with respect to the axis of the tension arm as shown. If it be assumed that the work frame is in its median or normal position, 55 as indicated in the drawings, it will be seen

that the spring 31 counter-balances the frame, acting upon the suspension system with an effective leverage which is constant for that position of the parts. If the work frame is then moved downward by the operator, if the machine is a pantograph machine, or by the jacquard or automat in the machine shown, the lever arm 17 will be swung to the left in Fig. 3, carrying with it the tension arm 34. This movement increases the tension of the spring 31 and the frame would therefore be over-balanced but for the fact that the roller 24 of the lever arm 17 travels outwardly on the bearing surface 35 of the tension arm 34, by reason 75 of the relative displacement of the lever arm and tension arm so that, while the tension of the spring 31 is increased the leverage through which it must then act upon the suspension system is increased and the 80 counter-balancing force therefore remains substantially constant. It will also be seen that if the work frame 36 is moved upwardly the lever arm 17 will be moved to the right, the tension arm 34 will also move 85 to the right and the tension of the spring 31 will be decreased, but the roller 24 will move inwardly on the tension arm 34 and the leverage through which the counter-balancing spring then acts will therefore be 90 decreased so as to compensate for the decrease of tension and the counter-balancing force delivered by the spring to the suspension system will remain practically constant.

I claim as my invention:—

1. In an embroidering machine, the combination of a machine frame, a work frame, an interconnected suspension system including a lever arm through which the counterbalancing force is applied, a counterbalancing spring, a tension lever moving with the spring, said tension lever and lever arm having the one a substantially radial bearing surface and the other a bearing on such bearing surface, and devices whereby the leverage through which the tension arm acts upon the lever arm is varied with the varying tension of the spring.

2. In an embroidering machine, the combination of a machine frame, a work frame, an interconnected suspension system including a lever arm through which the counterbalancing force is applied, a counterbalancing spring and a tension arm moving with the spring and operatively engaged with said lever arm, the lever arm and the tension arm being mounted on separate axes and having a movable engagement the one with the other.

3. In an embroidering machine, the combination of a machine frame, a work frame, an interconnected suspension system including a lever arm through which the counterbalancing force is applied, a coiled counter-

EUGENE NABEL,
D. I. MURPHY.

Copies of this patent may be obtained for five cents each, by addressing the "Commissioner of Patents, Washington, D. C."

Correction in Letters Patent No. 1,123,504.

It is hereby certified that the name of the assignee in Letters Patent No. 1,123,504, granted January 5, 1915, upon the application of Karl Eggart, of Arbon, Switzerland, for an improvement in "Embroidering-Machines," was erroneously written and printed as "the firm of Adolph Saurer," whereas said name should have been written and printed as *Firma Adolph Saurer*, as shown by the records of assignments in this office; and that the said Letters Patent should be read with this correction therein that the same may conform to the record of the case in the Patent Office.

Signed and sealed this 16th day of March, A. D., 1915.

[SEAL.]

J. T. NEWTON,

Acting Commissioner of Patents.
